UNITED STATES PATENT OFFICE.

RAYMOND L. WEGEL, OF NEW YORK, N. Y., ASSIGNOR TO WESTERN ELECTRIC COMPANY, INCORPORATED, OF NEW YORK, N. Y., A CORPORATION OF NEW YORK.

ACOUSTIC DEVICE.

Application filed April 30, 1923. Serial No. 635,407.

This invention relates to acoustic apparatus, the object being to provide an acoustic device capable of faithfully and efficiently producing sound vibrations within the auditable range.

In accordance with the general features of the invention, there is provided an improved form of diaphragm and mounting whereby the system may have symmetrical modes of vibration, sensibly such that if the lowest mode gives sharp resonance, it will be well below the voice range, or if it gives broad resonance it may be in the lower part of the voice range, and means for matching the impedance of the driving element to that of the diaphragm whereby the vibrations may be efficiently and faithfully transmitted.

In one of its embodiments the invention provides an acoustic device wherein a conical diaphragm having such dimensions, stiffness, and weight of material that when supported by a plurality of light flexible members substantially radially from a support coaxial with the diaphragm, its fundamental mode, if prominent, is enough below the voice range to prevent hollow or tubby quality of voice reproduction, but is not so low as to be below the lowest frequency of the musical range.

Another feature of the invention is the connection of the actuating device or driving member to the diaphragm or driven member by a lever system having the proper ratio to equalize the mechanical impedance of the driving and driven members.

It is a well known fact that notes low in the musical scale are heard less distinctly than those high in the scale. This may be due to the ear being less sensitive to the lower frequency tones, giving the impression that less energy is involved in producing them. However, more pleasing effects may be obtained if the lower notes can be produced more distinctly. The horns usually employed in connection with talking machine and loud speaking receivers are inefficient transformers of acoustic vibrations at the frequencies for which the ear is less sensitive. In many cases, therefore, the low notes appear to be entirely eliminated. It has been found that large diaphragms, when properly designed,

reproduce the lower notes very efficiently. Other things being equal, the larger the diaphragm the lower its fundamental mode of vibration and the same diaphragm, when free, has a lower natural period than when rigidly secured at its periphery. In this respect diaphragms are quantitatively analogous to open and closed pipes. In accordance with the invention a diaphragm preferably conical in form to permit the use of light materials and obtain the proper amount of stiffness is provided with a flexible mounting such that for low frequency substantially the whole of the diaphragm may vibrate. This arrangement possesses certain of the advantages of a free diaphragm and has a further advantage of added stiffness whereby the circular symmetry of the diaphragm is maintained while vibrating. The invention also provides for matching the impedance of the actuating device to that of the diaphragm whereby the most efficient transformation of energy is obtained.

A loud speaking receiver of the type herein described has preferably a fundamental mode of vibration below the voice range, that is, between 30 and 70 cycles per second, but not below the lowest vibration in the musical range which is about 16 cycles per second. Such a device will faithfully and uniformly transmit vibrations throughout the voice range and will amplify the low frequency vibrations in the musical scale to the extent that they will have the proper relative sound intensity with respect to the higher frequency vibrations.

In accordance with another feature a loud speaking receiver is provided in which a loud speaking unit comprising a large conical diaphragm, its mounting and the actuating member are supported on a sounding board, or a secondary diaphragm, constituting the rear wall of a cabinet, the front wall of which is apertured to freely receive the diaphragm and wherein are provided one or more resonant chambers for emphasizing vibrations of any desired frequencies.

In the drawing, Fig. 1 is a sectional view of a loud speaking receiver embodying the invention;

Fig. 2 is a rear view of the device shown in Fig. 1, showing the supporting means for the diaphragm;

Fig. 3 is an enlarged detail view of the diaphragm and the supporting means;

Fig. 4 is a cross sectional view of one form of actuating means that may be used;

Fig. 5 shows in cross section a modification of the diaphragm supporting means;

Fig. 6 is a rear view of the device shown in Fig. 5;

Fig. 7 is an enlarged detail view showing the method of supporting the diaphragm in Fig. 5;

Fig. 8 shows in cross section one form of mounting for the receiver; and

Fig. 9 is a front view of the mounting shown in Fig. 8.

A standard 10 carries at its upper end a horizontal member 11, to one end of which is attached an actuating device 12. A conical diaphragm 13 is supported on the horizontal member 11 by means of radially extending members 14 and is operatively associated with the actuating device 12 by means of a rod 25. The diaphragm supporting members 14 are preferably of a light flexible material such as rattan, or aluminum, and may be attached in any suitable manner to a collar 26, adjustably secured to the horizontal member 11 by means of screws 17. Preferably, the collar 26 is adjusted so that there will be no tension exerted on the diaphragm 13 by the rod 25. The diaphragm 13 is preferably made of a light elastic material such as paper, and is provided with a reinforcing annulus 18 at its periphery to stiffen it and maintain its symmetry while vibrating. The annulus 18 also forms a suitable means to which the supporting members 14 may be cemented or otherwise attached.

The actuating device 12 may be of any well known type of receiver magnet system, but it is preferable to use one of the type described in Patent No. 1,365,898 of January 18, 1921, to H. C. Egerton, modified as shown in Fig. 4, wherein the armature 15 is connected to the diaphragm 13 through a lever system comprising an intermediate lever 19, preferably a reed type lever, one end of which is connected to the armature 15 by means of rod 16, and the other end of which may be supported on the pole piece 8 in any suitable manner. The rod 25 connects the diaphragm 13 to a point intermediate the ends of the lever 19. By providing the proper ratio of lever arms the mechanical impedance of the actuating device may be matched to that of the diaphragm thereby providing the most efficient arrangement for transforming the energy delivered to the armature 15 into sound vibrations.

A diaphragm having a diameter of about 18 inches coupled to the receiver system here-

in described through a lever system having a reduction ratio of approximately two to one gives excellent results. However, in any case the proper ratio will depend upon the characteristics, including the dimensions, of the diaphragm and the characteristics of the actuating means used.

In the modification shown in Fig. 5, the diaphragm 13 is reinforced by a frusto-conical member 24 preferably made of the same material as the diaphragm itself. The outer edge of the member 24 is cemented, or otherwise attached, to the periphery of the diaphragm 13. The two members thus provide a hollow chamber within which the element 12 may be located. To the inner edge of the member 24 is attached the annulus 20 to which the supporting members 27 are secured which in turn are carried by the collar 26.

A receiver of the character shown in Fig. 1 or Fig. 5 may be mounted in a cabinet as shown in Figs. 8 and 9 and supported therein on a sounding board, or diaphragm, 22 which may constitute the rear wall of the cabinet. The sounding board 22 is preferably made of wood and so designed as to have a lower frequency of free vibration than that of the diaphragm 13. The front wall 21 is provided with an opening slightly larger than the diaphragm 13 and the space between the edge of the diaphragm 13 and the edge of the opening is closed by an annular membrane 23 which should be formed of a very light material such as will offer no resistance to the movements of the diaphragm 13. In the cabinet there may be provided one or more resonant chambers 28. The sounding board 22 and the resonant chambers 28 are preferably designed so as to be resonant for vibrations of such frequencies as it may be desirous to emphasize.

Although the invention has been described in connection with a loud speaking receiver, obviously it may be readily adapted to a transmitter, or a phonograph reproducer by substituting means well known in the art for the actuating device described.

The invention claimed is:

1. An acoustic device, comprising a conical diaphragm, and a resilient means peripherally supporting said diaphragm, said means extending substantially radially from the axis of said diaphragm.

2. An acoustic device, comprising a conical diaphragm having a low natural period, and means for peripherally supporting said diaphragm whereby it may vibrate substantially in accordance with its free mode of vibration, said means comprising a plurality of resilient members.

3. An acoustic device comprising a conical diaphragm and resilient means supporting said diaphragm at intervals, said means com-

prising a plurality of members extending substantially radially inward from the periphery of said diaphragm.

4. An acoustic device, comprising a conical diaphragm having a definite impedance, an actuating device having a different impedance, means comprising a system of levers for connecting said actuating device to said diaphragm and matching their impedances and resilient radially extending means for supporting said diaphragm.

5. An acoustic device comprising a conical diaphragm having a fundamental mode of vibration below the voice range and within the musical range, and resilient means peripherally supporting said diaphragm at intervals, said means extending radially inward from the periphery of said diaphragm.

6. An acoustic device comprising a large direct-acting diaphragm, a support substantially concentric with said diaphragm, and of less diameter than said diaphragm, and resilient supporting means connecting the diaphragm with said support.

7. An acoustic device comprising a large direct-acting diaphragm, means for actuating said diaphragm in accordance with sound, a base member, a collar support mounted on said base member, said collar being substantially concentric with and of smaller diameter than said diaphragm, resilient supporting means connecting the edge portion of the diaphragm with said collar, and means for supporting said actuating means from said base member.

8. In a sound reproducer, a large direct-acting diaphragm of light flexible material,

a central support, an actuating device mounted on said support and operatively coupled to said diaphragm to actuate the same in accordance with sounds, and diaphragm-supporting means also attached to said support and to said diaphragm at a distance from the point of attachment of said actuating device to the diaphragm, the connection through said support from the portion of the diaphragm attached to the supporting means to the point of attachment of the diaphragm to said actuating device being flexible to permit the said portion and said point of the diaphragm to be readily shifted with respect to each other.

9. A loud speaker comprising a large direct-acting diaphragm formed to possess inherent stiffness in the direction of axial movement, a central mounting, means secured thereto for vibrating said diaphragm in accordance with sounds to be produced, and flexible supporting means attached to the diaphragm at its peripheral portion and extending inwardly to said mounting for maintaining the circular symmetry of said diaphragm while permitting free vibration of its peripheral portion.

10. An acoustic device comprising a vibratable member, driving means therefor attached to said member, a flexible support for said member rigidly attached thereto and extending inwardly from the edge of said member and an apertured member for holding said support and said driving means.

In witness whereof, I hereunto subscribe my name this 28th day of April A. D. 1923.

RAYMOND L. WEGEL.
